UNITED STATES PATENT OFFICE.

SAUL KAUFMAN, OF NEW YORK, N. Y.

WINDOW GUARD.

Application filed June 26, 1920. Serial No. 391,990.

To all whom it may concern:

Be it known that I, SAUL KAUFMAN, a citizen of Russia, and a resident of the city of New York, borough of Manhattan, in the 5 county and State of New York, have invented a new and useful Window Guard, of which the following is a full, clear, and exact description.

This invention relates to window guards, 10 and has for an object to provide an improved construction which will automatically act to cover any goods adjacent the window to prevent theft thereof.

Another object of the invention is to provide 15 a window guard in which a covering member is provided associated with means for shifting the covering member quickly when released.

A still further object of the invention is 20 to provide an improved arrangement for show windows wherein means are provided for covering automatically and quickly the goods in a window in case the window is broken by an article being forced through 25 the window.

In the accompanying drawing:

Figure 1 is a fragmentary perspective view of a show window with a guard embodying the invention applied thereto.

30 Figure 2 is a fragmentary sectional view through Figure 1 approximately on line 2—2, the same being shown on an enlarged scale.

Referring to the accompanying drawing 35 by numerals, 1 indicates a platform for the display of articles adjacent the window 2, which is provided with a large pane 3 of glass whereby the articles on the platform 1 may be readily observed by persons on the street. In jewelry shops and other places 40 extremely valuable articles are found displayed in the show windows and occasionally a thief has broken the window in daylight in order to secure as many of the articles as possible in a very short time. Usually 45 the thief will break the window and gather one or two handfuls of the articles and then run away before an alarm can be sounded or any one can be secured to make 50 an arrest. In order to prevent a theft of this kind the arrangement shown in the drawing has been provided wherein a covering member 4 of leather, canvas or other strong material is provided, and mechanism 55 is also provided associated therewith for

quickly moving the covering 4 over the articles on the platform 1 as soon as the window-pane 3 has been broken. This will prevent a thief from readily securing the articles through the broken window, though, of course, if ample time was given the thief could cut or remove the covering 4. Usually if there is a delay of one or two minutes the thief will be caught, and consequently the delay caused by having the cover 4 automatically move over the articles will prevent theft in the manner above indicated.

In order to cause this quick moving of the cover 4 over the articles said cover is wound on a roller 5 which is supported in suitable 70 journal brackets 6, and if desired provided with a re-winding spring. The outer or free end of the cover 4 is connected to the cross-bar 7 of the frame 8 which frame is journaled in suitable brackets 9 adjacent the 75 rear of the platform 1. Springs 10 are provided which continually act on the frame 8 to give the same a tendency to move pivotally in its supporting brackets 9. Whenever the frame is permitted it will quickly 80 move upwardly in its pivotal brackets 9 until the bar 7 snaps into the hook 11, which hook is pressed by a spring 12 and is pivotally mounted on a suitable rigid frame 13 at the rear of the platform 1. In order that 85 the cover 4 may remain rolled on the roller 5 and the goods properly displayed on platform 1, a catch 14 is provided having a locking bar 15 normally overlapping the bar 7, as shown in Figure 2, and held in that position by a pivotally mounted catch member 16 against the action of spring 17. When 90 the catch member 16 is released spring 17 will immediately force bar 15 longitudinally away from the bar 7 whereby it is released 95 and the springs 10 will be permitted to quickly raise the frame 8 and spread the cover 4 over and in front of the articles on platform 1. In order that the catch member 16 may be actuated whenever the window-pane 3 is broken a comparatively stiff frame 18 is provided and arranged so that the lower bar thereof will be adjacent the upper part of the catch 14 so that when the frame is swung inwardly the catch member will be operated 100 and bar 15 released. A comparatively coarse mesh 19 is connected with frame 18, said mesh being either textile material or wire as preferred. Frame 18 is suspended 105 by suitable cords 20 from the upper part 110

of the window 2, whereby whenever an article, as for instance a brick, is thrown through the windowpane 3 it will strike some of the wires of mesh 19 and will swing 5 the frame 18 inwardly a short distance and against catch 16 whereupon the catch member 16 will be released and bar 15 moved away from bar 7.

In addition to causing the covering member 4 to quickly move over the articles and thereby protect the same against quick removal, a bell 21 is provided for sounding an alarm. A number of different circuits could be provided for this bell, but as shown in 15 Figure 2 a double arrangement of circuit is found to be a desirable arrangement to quickly cause the bell to sound. The hook 11 is provided with an insulating member 22 which carries a metal contact member 23 into 20 which the bar 7 fits when the bar has been released. A suitable source of current 24 is connected with the frame 8 in any suitable manner, and also with one terminal of bell 21. The opposite terminal of bell 21 is connected to the contact member 23 so that when 25 the bar 7 is in engagement with said contact member the circuit of bell 21 will be closed and the bell will of course be operated. In addition to this circuit a spring 25 is arranged in the path of movement of the bar 15 so that as soon as said bar is released by the catch member 16 contact will be made 30 between the catch 14, bar 15 and spring 25. Spring 25 is connected by a suitable wire 35 with one side of the bell 21 while the catch 14 is connected by a suitable wire to one side of the source of current 24. Other circuits may be used, but these have been shown as 40 illustrating the idea of providing a quick alarm as soon as the catch has been released as well as a quick and automatic covering of the articles in the window.

What I claim is:

1. In a show window structure provided 45 with a pane of glass and a floor adapted for

the display of goods, a window guard comprising a covering member adapted to be spread over said floor, a roller connected with said covering member and on which the covering member is normally wound, a 50 spring actuated frame connected to one end of said covering member designed to be swung upwardly and cause the covering member to be unwound and moved over said floor, said frame being hinged at the rear 55 of said floor, a hook arranged adjacent the rear of said window structure for engaging said frame and locking the same in a raised position, a catch arranged at the front of said floor near the pane of glass in said window adapted to normally hold said frame against movement whereby the covering member will be maintained on said roller and means suspended near one face of said pane designed to release said catch when 60 pressed toward the rear of said structure.

2. In a show window structure provided with a pane of glass and a floor adapted for the display of goods, a window guard comprising a covering member, a roller on which 70 said covering member is normally wound, a stiff frame having the front thereof connected with one edge of said covering member, means for pivotally connecting the rear edge of said frame to said floor near the rear 75 thereof, spring means acting on said frame for giving the same a tendency to swing to the rear of the window structure, a catch at the front of the floor for holding the frame normally against movement, means spread 80 adjacent to the front of said floor and in the rear of the glass in said window for releasing said catch when moved toward the rear of the window structure, and a hook arranged near the rear of the window structure for 85 interlocking with said frame when the frame is moved into engagement therewith, for locking the frame against movement.

SAUL KAUFMAN.
